US00D723035S

(12) **United States Design Patent**
Taniho et al.

(10) **Patent No.:** **US D723,035 S**
(45) **Date of Patent:** **** Feb. 24, 2015**

(54) **SCANNER**

- (71) Applicant: **PFU Limited**, Kahoku-shi, Ishikawa (JP)
- (72) Inventors: **Kiichi Taniho**, Kahoku (JP); **Shigeru Yonemura**, Kahoku (JP); **Toshiki Satoji**, Milan (IT); **Takashi Kirimoto**, Milan (IT)
- (73) Assignee: **PFU Limited**, Ishikawa (JP)

(**) Term: **14 Years**

(21) Appl. No.: **29/499,542**

(22) Filed: **Aug. 15, 2014**

(30) **Foreign Application Priority Data**

- Apr. 15, 2014 (JP) 2014-008235

(57) **CLAIM**

The ornamental design for a scanner, as shown and described.

DESCRIPTION

FIG. 1 is a front perspective view of a scanner showing our new design;
FIG. 2 is a front view thereof;
FIG. 3 is a rear view thereof;
FIG. 4 is a top plan view thereof;
FIG. 5 is a bottom plan view thereof;
FIG. 6 is a left side view thereof;
FIG. 7 is a right side view thereof;
FIG. 8 is an enlarged fragmentary top plan view thereof, taken along line 8-8 and in the direction of arrows in FIG. 4;
FIG. 9 is another perspective view of the scanner with both catch and paper feed trays shown in an open position; and,
FIG. 10 is another perspective view of the scanner with a paper feed tray shown in an open position.
Broken lines and entirely unshaded portions contained within broken line are not claimed.

1 Claim, 7 Drawing Sheets
